T. A. WESTON, OF BUFFALO, NEW YORK.

Letters Patent No. 75,089, dated March 3, 1868.

IMPROVEMENT IN RATCHET-HEAD AND LEVER.

The Schedule referred to in these Letters Patent and making part of the same.

TO ALL WHOM IT MAY CONCERN:

Be it known that I, T. A. WESTON, of the city of Buffalo, in the county of Erie, and State of New York, have invented a certain new and useful Improvement in Ratchet-Levers or Heads; and I do hereby declare that the following is a full and exact description thereof, reference being had to the accompanying drawings making part of this specification.

Figure 1 is a plan of the head of my improved ratchet-lever, the pawl-disk being in section of plane $x x$, fig. 2.

Figure 2, a vertical section in plane $y y$, fig. 1.

Like letters of reference designate corresponding parts in both figures.

The object of my invention is to dispense with fine teeth in the ratchet, which are rapidly worn away, and to substitute an arrangement which is enduring, and which will produce as nice and accurate an adjustment as the fine teeth.

As represented, A is the head of the lever, which is shown broken off. This head is made hollow, and has cut upon its inner periphery, at regular distances apart, a series of teeth, e e, with inclined planes on one side and abrupt shoulders on the other, as usual. I prefer to make the shoulders obtuse-angled, as sustaining the greater wear, and as being more particularly adapted to the pawls hereafter described, but, if desired, right or other angled shoulders may be employed. Within the hollow head of the lever is fitted a pawl-disk, B, held in place in any suitable manner. This disk has an eye, a, of square or other form, which will receive and hold the article to be turned. It also has pawls or sliding bolts e e, fitting in suitable sockets of the disk, which pawls are forced out or protruded to engage with the teeth before described by springs d d. The ends of the pawls are preferably rounded so as to work easily over the teeth. In the drawings the pawls are shown as arranged on opposite sides, at right angles to each other, in order to fit the obtuse shoulders of the teeth; but their position may be modified to any form of the teeth. The relative number of the pawls and the teeth is unequal, that is, the pawls are one less or one more in number than the teeth, preferably one less. In the drawings four pawls and five teeth are shown.

The operation will be readily understood. As each pawl ascends the inclined side of a tooth, it falls behind the shoulder of the same, and holds the pawl-disk to the lever while the latter is turned; but all of the teeth do not engage simultaneously, but rather in succession; that is, while each pawl is passing over the length of one tooth, all of the other pawls have successively engaged and performed their action. As the number of pawls and teeth may be considerable without injuriously reducing them in size, it is apparent at a glance that an equal number of adjustments and movements of the lever may be attained as would be attained were a greater number of fine teeth with a single pawl or catch used, while the wear and the strength are vastly increased. The great advantage of this arrangement thus consists in substituting for a great number of small teeth with a single pawl, which soon wear so as to be useless, and which insure but little power, an arrangement of large teeth and pawls, which produce the same nice degree of adjustment, but still insure a great power, and cannot soon wear out. The unequal relative number of the teeth and pawls insures this result.

It is obvious that this combination of the teeth and pawls can be applied to almost any arrangement of ratchet-levers or heads. I show but one form, but do not confine myself to it. The flat form of the ratchet-head shown in the drawings enables the same to be applied in narrow spaces for turning, where other forms could not be applied.

I claim the ratchet-lever head, when constructed with teeth e e e e and pawls e e e e, combined, arranged, and operating substantially as and for the purposes shown and described.

In witness whereof, I have hereunto signed my name in the presence of two subscribing witnesses.

T. A. WESTON.
